UNITED STATES PATENT OFFICE

HAROLD G. DAVIS, OF DENVER, COLORADO, ASSIGNOR TO THE DAVIS AND SON MANUFACTURING COMPANY, OF DENVER, COLORADO, A CORPORATION OF COLORADO

OIL-DISPENSING DEVICE

Application filed April 20, 1928. Serial No. 271,503.

This invention relates to improvements in oil dispensing devices of the type shown and described in United States Letters Patent No. 1,601,200, granted to me on September 28, 1926.

It is customary for gasoline service stations to dispense lubricating oil in measured quantities and for the convenience of serving clients with lubricating oil, it is desirable to have an apparatus from which the oil can be quickly drawn into measures. In the patent above identified, a device of this type has been shown and described in which the oil is contained in a tank located under ground and subjected to sufficient air pressure to cause it to flow upwardly through pipes to the dispensing valves.

It has been found that it is often desirable to provide a dispensing device which will be self-contained and which can therefore be put in place without the necessity of excavating for the purpose of placing tanks underground.

It is the object of this invention to produce an oil dispensing device which shall be so constructed that it can be quickly put into place on any level supporting surface and which shall have a base that contains a plurality of airtight tanks which are adapted to contain different grades of lubricating oil. Extending upwardly from the base is a display device having a dispensing head from opposite sides of which dispensing valves project. These dispensing valves are controlled by means of a spring and the oil containing tanks are subjected to sufficient air pressure to cause the oil to flow upwardly to the dispensing valves.

Having thus briefly described the invention, the same will now be described in detail, and reference for this purpose will be had to the accompanying drawings in which the preferred embodiment thereof has been illustrated and in which:

Fig. 1 is a side elevation of one of my improved oil dispensing devices showing portions thereof broken away for the purpose of more clearly illustrating the construction;

Fig. 2 is a transverse section taken on line 2-2, Fig. 1;

Fig. 3 is a vertical section taken on line 3-3, Fig. 1;

Fig. 4 is a transverse section taken on line 4-4, Fig. 1;

Fig. 5 is a section taken on line 5-5, Fig. 2;

Fig. 6 is a vertical section similar to that shown in Fig. 3, but showing a slightly modified form of tank; and

Fig. 7 is a vertical section taken on line 7-7, Fig. 6.

In the drawing numeral 1 designates a cast iron ring which is adapted to rest upon the supporting surface 2 and which has an upwardly extending flange 3, which cooperates with the enclosing shell 4. Ring 1 is also provided with a plurality of supporting bars 5 that have their ends welded to the ring and which serve as supports for the oil tanks A and B. These oil tanks have a transverse section like that shown in Fig. 4 from which it will be seen that one side is formed by a metal plate 7, that is curved in the arc of a circle and has its edges secured to the edges of the flat plates 8 and 11. These tanks are provided with tops 9 and bottoms 10 and are of unequal size. The tanks when in place within the casing are so located that the curved sides 7 are concentric with the enclosing shell 4 in the manner shown in Fig. 4. The width of the tanks is less than the radius of the circular shell 4 so that when these tanks are put into place there will be a space C between the vertical sides 8. This space provides a passageway through which the discharge pipes 12 may pass and they also provide a space for the reception of the electric heaters 13. These heaters are secured to the upper ends of brackets 14 by means of screws 15 and these brackets have their lower ends secured to the ring 1 by means of screws 16 in the manner shown in Fig. 1.

Further reference will be made to the electric heaters as these are considered to be an important part of this invention.

Resting on the upper edge of the cylindrical enclosing shell 4 is another ring which has been designated by numeral 17. This ring has a downwardly extending flange 18 which fits within the upper end of the cylindrical shell in the manner shown in the draw-

60

ings. Extending diametrically across ring 17 is an integral member 19 having an elongated central opening 20 whose upper edge is provided with an upwardly extending flange 21. Extending across the ends of this opening are webs 22, which are provided with openings for the reception of bolts 23 to which reference will hereinafter be made. The parts of member 19 between the curved ends of the central opening 20 and the ring 17 are provided with a bottom 24 so as to form boxes 25 that can be employed for making electrical connections and for other purposes. The tops of these boxes are closed by means of removable covers 26 which are held in place by bolts 26'. Located above the opening 20 is a dispensing head 27, which is provided with a plurality of chambers with which dispensing valves 28 are in communication. This dispensing head is supported on the bolts 23 whose lower ends pass through openings in the webs 22. As this dispensing head has been described in my patent above identified, it will not be described in detail here. Supported on the dispensing head 27 are a plurality of glass jars 29 which contain samples of the oil with which the corresponding valves are in communication. The display jars are surmounted by an ornamental metal cap 30, which rests upon a base 31 that is secured to the dispensing head by means of bolts 32. A translucent globe 33 is secured to the top of the hood 30 and is adapted to contain a light which is periodically flashed. A metal shell 34 extends from the member 19 to the under surface of the dispensing head 27 and serves to enclose the space between the transverse member and the dispensing head so as to provide a chamber 40 through which the pipes 12 can pass. Each one of pipes 12 is connected to the lower end of one of the tanks A and B and has its other end connected to one of the chambers in the transverse dispensing head 27 so that each of the dispensing valves 28 is in communication with the bottom of one of the oil tanks via a chamber in the dispensing head.

In order to make the oil flow from the tanks to the valves 28, it is necessary to introduce air under pressure into the tank compartments in the space above the top of the oil and the top plate 9 of the tanks and for this purpose I have provided a system of pipes so that the air connections can be readily made. Located within the space C is an air-reducing valve 35, whose delivery port is connected to a cross 36. A safety valve 37 is connected to the top opening of the cross and a pressure gauge 38 is connected to the lower opening. The side opening farthest away from the reducing valve is connected with a T 39. From the opening in the bottom of the T 39 a brass tube 40 extends downwardly and is curved in the manner shown in Fig. 2. This tube is con-

nected at 41 and 42 with the interiors of tanks A and B on one side of the space C between the two sets of tanks. A similar tube 40a extends from the top of the T 39 and is connected with the interiors of the tanks A and B on the opposite side of space C at points 41a and 42a. From the intake opening of the reducing valve a pipe 43 extends to a T 44 to which the pipes 45 and 46 are connected. A valve 47 is located in pipe 43 between the T 44 and the reducing valve 35. Pipe 45 extends upwardly so that connection can be made with the air supply of the service station by means of an overhead pipe (not shown). If the air supply is so located that an underground pipe is preferable, the cap 48 can be removed from the lower end of pipe 46 and connection made with a pipe from the air tank. In this latter case pipe 45 can be removed and replaced by a plug.

Electric current for the heaters can be introduced through the conduit 49 and electric wires will pass through the flexible conduits 50 to the junction boxes 51 of the heaters. Secured to the upper ring 17 are two segmental shaped combined supporting tables and drip pans. These are each composed of a shallow pan 52, whose upper side is closed by means of a perforated plate 53. Each plate 53 is secured to a pan 52 by means of screws 54 so that the two parts will remain in assembled relation. These combined supporting tables and drip pans are of such size that they fit the space between the central member 19 and the inner surface of ring 17 in the manner clearly shown in Fig. 2. In dispensing oil it often times happens that a small amount of oil is spilt and this will pass through the perforations in plates 53 and will be retained in the pans 52. These pans can be emptied periodically. I consider the use of the combined drip pans and supporting tables to be a great improvement in this type of machine for the reason that it makes it unnecessary to have any pipe connections to a container for the purpose of taking care of the drip. By the construction shown, the drip pans and tables can be readily removed and replaced. It is quite often necessary to remove the drip pans so as to give access to the fill openings through which the oil is introduced into the tanks A and B. These fill openings are closed by screw plugs 57.

I desire to call particular attention to the great convenience in the installation of machines constructed in the manner described as they are entirely self-contained and can be quickly put in place on any flat supporting surface. The connections with the air and with the electric current supply can be readily and quickly accomplished as there are no underground pipes to be laid. The location of the air-reducing valve 35

within the device is a great convenience as the parts are located in such a way that they cannot be interfered with by unauthorized persons and they can also be put into place in the factory, thereby assuring good workmanship and tight connections. The electric heaters 13 are of great importance in colder climates, as without heaters of some sort, the lubricating oil will congeal to such an extent that it will not readily flow, and when this occurs the apparatus becomes practically inoperative. The space C between the two sets of tanks forms a compartment which contains the dispensing pipes 12 and therefore since the heaters are located in this compartment, these pipes will be kept warm, even during the coldest weather and besides this, the use of the compartment, as shown, makes it possible to more efficiently use the heat generated as it is stored in this compartment from which it is absorbed by the lubricating oil within the tanks.

In Figures 6 and 7 I have shown a modified construction in which the tanks corresponding to tanks A and B are arranged in superposed relation, that is to say there are two segmental shaped tanks B', one on each side of the compartment C and respectively disposed above two tanks A', which are also respectively located on opposite sides of the compartment C. The bottom of each tank B' rests upon the top of a tank A' as shown at 55. The delivery pipes 12 connect with these tanks near their bottoms and the air supply is connected with each tank near the top. Tanks B' have fill openings 56 that are closed by screw plugs 57. It is, of course, necessary to introduce oil into the lower tanks A' and this is accomplished by providing a tube 58 whose lower end extends through an opening in the contacting walls 55 of the tanks B' and A' to which it is secured as shown at 59. The upper end of each tube 58 extends through an opening in the top of the tank B' and is secured thereto as shown at 60. The upper ends of tubes 58 are closed by means of screw plugs 57.

The tanks A and B and A' and B' are formed independently and the individual tanks of each pair may be spot welded at different places or otherwise connected so that they are practically unitary as far as handling is concerned. It has been found that there is an important advantage in constructing the tanks separately as above explained, rather than forming large tanks and dividing them by partitions into separate compartments, since if there should be any leaks in the separate tanks, oil will become visible on the outside so that the leaks will be readily discovered, whereas if a partition is placed in a tank so as to divide it into two compartments, a leak in this partition would not be quickly discovered and therefore the two different grades of oil would intermix. The

term "pressure reducing valve assembly" as used in the claims must be understood to mean the reducing valve proper, the air gauge, the safety valve and their necessary pipe connections as best illustrated in Fig. 1 of the drawing. 70

Having described the invention what is claimed as new is:

1. An oil dispensing device having a hollow base, a plurality of oil storage tanks located in the base, some of said tanks having their adjacent surfaces spaced apart so as to form a chamber, oil discharge pipes in said chamber, said pipes being connected with the lower ends of said tanks and means for heating said chamber so as to maintain the oil in flowable condition during cold weather. 75

2. An oil dispensing device comprising, a base ring, a hollow enclosing shell supported on the ring, means for closing the upper end of the shell, a plurality of oil tanks also supported on the base ring, said tanks having adjacent walls spaced apart so as to form with the shell a chamber, an oil delivery pipe in communication with the interior of each tank near its bottom, means for delivering compressed air to the upper end of each tank, and means for heating the chamber so as to maintain the oil in flowable condition 90

during cold weather. 95

3. An oil dispensing device comprising, in combination, a base ring adapted to rest upon a supporting surface, an enclosing shell supported on said ring, a second ring supported on the upper end of said shell, said last named ring having a transverse member extending diametrically thereof, segmental cover portions supported on the last named ring and on the transverse member, a plurality of oil storage tanks located within the shell, some of said tanks having their adjacent sides spaced so as to form with the shell a chamber and means for heating the chamber. 100

4. An oil dispensing device comprising, in combination, a base ring adapted to rest upon a supporting surface, an enclosing shell supported on said ring, a second ring supported on the upper end of said shell, said last named ring having a transverse member extending diametrically thereof, segmental cover members supported on the last named ring and on the transverse member, a plurality of oil storage tanks located within the shell, some of said tanks having their adjacent sides spaced so as to form with the shell a chamber, dispensing pipes communicating with the lower ends of the tanks, compressed air pipes in communication with the upper ends of the tanks, and means for heating the chamber. 115

5. In an oil dispensing device, in combination, a base comprising a base ring adapted to rest upon a supporting surface, an enclosing shell supported on said ring, another ring supported on the upper end of the shell, said 120

last named ring having an integral transverse member provided with an elongated opening, cover members supported by the last named ring and by the transverse member, said member having recesses between the ends of the opening and the ring and covers for said recesses.

6. An oil dispensing device comprising, in combination, a hollow base, a plurality of 10 separate tanks located in the base, said tanks forming two groups, the tanks of each group being connected with each other, the two groups being separated a short distance so as to form with the wall of the base a chamber, 15 an oil discharge pipe in communication with the interior of each tank near its bottom, means for delivering compressed air to the upper end of each tank, and means for heating the chamber whereby the oil will be maintained in flowable condition during cold 20 weather.

7. An oil dispensing device comprising, in combination, a hollow base, a plurality of 25 separate tanks located in the base, said tanks forming two groups, the tanks of each group being connected with each other, the two groups being separated a short distance so as to form a chamber, an oil discharge pipe connected with each tank near its bottom, said 30 pipes extending upwardly through the chamber between the tanks, means for conducting air under pressures to each tank and means for heating the chamber.

8. An oil dispensing device, including a 35 hollow cylindrical base provided with a series of tanks, the said tanks being located within the base and arranged in groups located on opposite sides of a diameter of said base whereby a chamber is formed, means 40 for heating the chamber whereby the oil will be maintained in flowable condition during cold weather, an oil dispensing pipe connected with each tank near its bottom, each of the dispensing pipes extending upwardly to 45 a point above the upper ends of the tanks, a valve associated with the upper end of each pipe, and means for delivering compressed air to the upper end of each tank.

9. An oil dispensing device including a 50 base provided with a series of tanks, the said tanks being arranged in groups located on opposite sides of a central compartment with which the structure is provided, and oil dispensing pipes located in said compartment 55 and communicating respectively with said tanks.

10. An oil dispensing device, including a 60 portable base having a self-contained source of supply consisting of a plurality of tanks, an oil delivery pipe connected with each tank near the lower end thereof, said pipes extending upwardly to a point above the upper ends of the tanks, a valve associated with the upper end of each pipe, heating means 65 within the base adjacent the tanks for main-

taining the oil in flowable condition during cold weather, and means for applying air under pressure to the upper ends of the tank.

11. An oil dispensing device having a 70 hollow base, a plurality of oil storage tanks located in the base, some of said tanks having their adjacent surfaces spaced apart so as to form a chamber, oil transfer pipes connected with the interior of the tanks near their bottoms, the transfer pipes extending upwardly 75 beyond the tops of the tanks, the upper end of each pipe having a valve, means for connecting the upper ends of the tanks with a source of air under pressure, and means for heating the interior of the chamber so as to 80 maintain the oil in flowable condition during cold weather.

In testimony whereof I affix my signature.
HAROLD G. DAVIS.
